UNITED STATES PATENT OFFICE.

FREDERICK J. MILES AND DONALD C. THOMPSON, OF NEWARK, NEW JERSEY, AS
SIGNORS, BY MESNE ASSIGNMENTS, TO EUGENE SULLIVAN, OF NEW YORK, N. Y.

SOCKET FOR ELECTRIC LAMPS.

Application filed November 14, 1924. Serial No. 749,907.

Our invention relates more particularly to lamp sockets employed where vibration is present and where it is necessary to guard against the lamp working loose in the socket, 5 and more particularly for use on vehicles, such as automobiles, and especially for use in signal devices for such vehicles.

The object of our invention is to provide a socket which will insure perfect contact 10 and guard against the lamp working loose, thereby avoiding poor contact, or a contact becoming entirely separated, and also to insure clean contacts. A further object is to provide a construction having the least number 15 of parts, readily made and assembled, and which will permit extremely low cost of production.

To accomplish our objects we have designed a socket having only three parts, and 20 in which screws, rivets and brazed or soldered joints are entirely dispensed with. These parts comprise a base plate of insulating material and two contact members, one contact member being the socket or 25 sleeve for the lamp and the other being the bottom contact member. The socket member is a tubular metal piece having two oppositely located bayonet-lock slots and two projecting lugs by means of which the 30 socket is clamped to the base. The bottom contact member is stamped from sheet metal and bent into shape so as to present three elements: first, the contact end, which is bent into S-shape and which projects 35 through a gap into the socket member; second, a clamping element consisting of two laterally projecting lugs which are bent 40 downward to pass through two slots in the base plate and again bent to clamp the contact piece in position; and third, at the outer 45 end two upwardly projecting lugs for clamping a circuit wire connection.

In the drawing, Figure 1 is an elevation 45 of the socket with a lamp mounted therein and a circuit wire connected between the clamping lugs of the bottom contact member; Figure 2 is a top plan view of the socket; Figure 3 is a vertical section of the line 3-3 of Figure 2; Figure 4 a bottom plan view; Figure 5 a central vertical section 50 through Figure 2 taken at right angles to the line 3-3 and showing the clamping lugs for the wire connection in the open position; Figure 6 a vertical section illustrating the clamping lugs for the conduct- 55

tor in the closed position; and Figure 7 a cross section of the line 7-7 of Figure 6.

Referring now to the drawings, 10 indicates the metal sleeve or socket member having bayonet type slots as indicated at 11 and 12 adapted to receive the locking pins 14 projecting laterally from a metallic collar 15 on the base of lamp 13 and which collar constitutes one contact terminal of the lamp. The sleeve 10, at the end which is seated 15 upon the base plate 20 of insulating material, is provided with two oppositely located gaps 16 and 17 and preferably so located as to be diametrically opposite to the bayonet-slots, and projecting from the end of the 20 sleeve in line with the two bayonet-slots are lugs 18 and 19 which are inserted through slots 21 and 21^a in the base plate and bent over as shown in Figures 3 and 4 to clamp the sleeve member 10 firmly upon the base 25 plate. The base plate 20 may be of any desired shape but preferably is of the shape shown in Figures 2 and 4 and is provided with two centrally located slots 21 and 21^a 30 for the socket member already referred to, and two similar slots 28 and 28^a located closer together, and near one end of the base plate for receiving the bottom contact lugs. The base plate also is provided with holes 35 to receive pins or screws whereby same may be secured to any desired support or fixture or within an automobile lamp chamber. The bottom contact member of the socket is stamped in one piece from pliable sheet metal such as brass or copper in the form 40 of a long narrow strip with four projecting lugs 26, 27, 31, and 32, lugs 26 and 27 being bent downward for the purpose of passing through slots 28 and 28^a in the base plate 45 and long enough to be bent over as indicated in Figure 4 so as to clamp this contact member in position on the base plate. The other two lugs 31 and 32 are bent upward prepared to receive a circuit wire and clamped 50 as will be presently explained. The opposite end of the contact member is preferably bent into approximately S-shape as best indicated in Figure 5, the lower portion thereof being approximately parallel with the base plate and having a return bend 23, and 55 a second bend which forms the contact 24 which as shown is positioned centrally within the sleeve 20 so as to make contact with the bottom terminal 22 of the lamp base as indicated in Figure 3. The contact end 24 60

100

110

is so positioned vertically within the sleeve 10 that when the lamp is inserted the bottom contact 22 of the lamp will engage the contact 24 before the pins 14 reach the locking ends of the bayonet-slots so that as the lamp is pressed into locking position the spring contact 24 will be under considerable pressure tending to push the lamp upward and holding lamp pins 14 firmly within the bayonet-lock. When thus inserting the lamp and applying pressure to the spring contact it will readily be observed that the act of bending the bottom contact will produce a relative rubbing action between contacts 22 and 24 thus insuring a clean contact. The purpose in having two gaps 16 and 17 in the sleeve member 10 is first, to provide an entrance for the spring contact member 24 and secondly, to guard against the curved portion 23 coming in contact with the sleeve. Another advantage in providing the two gaps is that no mistake can be made in mounting the sleeve upon the base plate since it makes no difference which of the two gaps 16 and 17 are adjacent to the slots 28 and 28^a of the base plate. For the purpose of facilitating the attachment of a conducting wire to the bottom contact strip the hole 30 positioned between the lugs 31 and 32 is provided and when attaching a circuit wire the end is bared of insulation and inserted downward through the hole 30 and then bent under and over the end of the plate and back between lugs 31 and 32 parallel with the covered portion of the conductor as shown in Figures 5 and 6 and thereupon lug 31 is bent firmly against the conductor, a pair of ordinary pliers being employed for the purpose, and then lug 32 is similarly bent over, overlapping lug 31 as illustrated in Figures 6 and 7. Thus a firm contact is obtained without the use of screws, or solder.

This form of socket is especially designed for use where the fixture or other device upon or within which the socket is mounted, forms part of a grounded circuit, and with this in view the lugs 18 and 19 are designed to be held in contact with such metallic support when secured in place by screws or pins passed through the holes in the base plate.

From the foregoing it may be observed that the construction of our improved lamp socket is extremely simple and as above stated comprises only three parts and does away entirely with screws, rivets or soldered joints, and it is also evident that this form

of socket will withstand extreme jarring and considerable vibration without any liability of the parts becoming loose in such manner as to result in poor contact or a broken circuit.

Having thus described our invention, we claim as new and desire to secure by Letters Patent:

1. An electric lamp socket consisting of three pieces, one, a base member of insulating material having a plurality of slots formed therein; two, a cylindrical contact member having two oppositely located bayonet-lock slots adapted to receive the laterally projecting pins of a lamp base, a slot or gap for receiving the other contact element, and two oppositely located lugs adapted to pass through slots in the base piece and to be bent over for clamping same to the base piece and which lugs are adapted to make contact with a metallic piece included in a grounded circuit; and three, a spring contact member projecting into said cylindrical piece and having downwardly projecting lugs passing through slots in said base piece and bent over to clamp same in position and also having lugs for clamping a circuit wire to said contact member.

2. An electric lamp socket consisting of three pieces, one, a base member of insulating material having a plurality of slots formed therein; two, a cylindrical socket contact piece having two oppositely located bayonet-lock slots adapted to receive the laterally projecting pins of a lamp base, two oppositely located gaps in the lower end of said socket piece and positioned diametrically opposite to the bayonet-lock slots, two oppositely located lugs projecting from the lower end and adapted to pass through slots in the base piece and to be bent over for clamping said socket and base together, and which lugs are adapted to make contact with a metallic piece included in a grounded circuit; and three, a spring contact piece projecting into said socket member through one of the gaps and having downwardly projecting lugs passing through slots in said base and bent over to clamp same in position, lugs at the outer end for clamping a circuit wire thereto and the inner or contact end of said piece being bent into the form of a letter S.

This specification signed this 13th day of November, A. D. 1924.

FREDERICK J. MILES.
DONALD C. THOMPSON.
